UNITED STATES PATENT OFFICE.

WINFIELD SCOTT WILLIAMS, OF CHICAGO, ILLINOIS.

FLUID COMPRESSOR.

Application filed December 19, 1921. Serial No. 523,388.

To all whom it may concern:

Be it known that I, WINFIELD SCOTT WILLIAMS, a citizen of the United States, residing at Chicago, in the county of Cook and State of Illinois, have invented a new and useful Improvement in a Fluid Compressor, of which the following is a specification.

My invention relates to improvements in fluid compressors, and more especially in application to refrigerating or ice machines in which is employed the cold producing property of expanding gas liquefiable under mechanical compression.

Among my primary objects are a small number of parts, a small number of working parts, simplicity of assemblage and disassembly, strength and durability of parts, efficiency with sustained delivery, automatic increase of efficiency, oil and gas proof, a minimization of valves, easy access to valves, large valves and large bearing surfaces insuring positiveness, automatically self cleansing valves, automatic modification of temperature by utilization of the fluid medium, and other objects which will appear herein.

The drawings illustrate an embodiment of my invention, but I do not limit myself to this detail construction as many variations will appear to one conversant with the art.

Figure 1 is a sectional elevation showing internal form and assemblage.

Figure 2 is a sectional elevation at right angles to Fig. 1 on line 2—2, as indicated by arrows.

Figure 3 is a broken section of a valve seat and valve.

Figure 4 is a sectional elevation of a piso ton and valve assemblage along line 4—4, of Fig. 2.

Figure 5 is a cross-section of a cylinder head on line 5—5, Fig. 1.

Figure 6 is a cross section on line 6—6, Fig. 1; and

Figure 7 is a cross section on line 7—7, Fig. 2.

Although my invention is in the broad field of compressors, I desire to more particularly describe it as related to the compression of such fluids as carbon dioxide. In the compression of such fluids converting the same from a gaseous state to a liquid state to secure efficiency, durability, and economy, is to attain a much to be desired quality. As illustrated, my housing struc-

ture is composed of two parts 1 and 10, the two being joined in such approved method as I may deem best. The unitary element 1 consists of a crank housing, an oil reservoir, a cylinder head; and a cylinder with an integral gas jacket; the element 10 associated with element 1 forms a unit having only one joint, and that one so related the mechanism is easily made oil tight and gas tight; the union being preferably below the line of the shaft. The said unit is provided with a boss 2 being designed as the shaft 12 opening and a bearing, a boss 3 having a bore 16 designed as a shaft bearing, opening only into a crank case 9; also a valve seat opening 4. A cylinder 6 having a spaced area 7 concentric therewith communicates with said spaced area 7 through ports 8', and said spaced area 7 communicates with an external source of supply through a port 8; the cylinder further communicating with a chamber 9, which chamber 9 is enclosed by a base 10 containing cylinders or wells 11; 12 is a driving shaft connected with a source of power.

This shaft 12 is provided with a collar 13 and an eccentric 19 fixed thereto;—said eccentric 19 preferably threaded thereon at 85 14 and securely locked by a nut 15. A bore 16 in boss 3 forms the bearing for one end of shaft 12, and in said end of shaft 12 there is provided a thrust pin 17 and coiled spring 18 operating in a bore 18 designed 90 to secure a longitudinal tension upon said shaft 12. Eccentrics 19 are unitary as related to each other, and are unitary with shaft 12 when the device is assembled for action, but they are removable for disassembly. Eccentric straps 20 operating on eccentrics 19 are journaled on wrist pins 22, fixedly a part of drive arm 21. The said drive arm 21 has on either end thereof and unitary therewith pistons 23 and 23'; 23' being designed, primarily, as a guide to sustain the more perfect alignment of piston 23 of drive arm 21. Piston 23 has a plurality of rings 24 thereon; ports 25 transversely perforating the piston and communicating with a longitudinal bore 26; said longitudinal bore 26 terminating at one end in a conical valve seat 27 and at the other end in an enlarged bore separated by a flange 36. Functioning in said bore 26, I provide a valve having a substantially triangular stem 28, ports 29 transverse

thereof adapted to register with ports 25 in piston 23, and communicating with a longitudinal bore 30 which said bore 30 communicates with ports 32 transversely perforating the said valve at the base of a conical head 33 and registering with an annular groove 31.

The valve stem 28 is shown having three sides—triangular form in cross section, but 10 the same is intended to indicate a plurality of sides but not to any limit of number or form. This piston valve is readily accessible through opening 4 in the cylinder head; said valve construction and arrangement is 15 specially designed for efficiency and self-cleansing, the passage of the fluid medium along the sides and coming into contact at 32 with the fluid medium driven through bore 30 and passing around valve head 33 20 cleanses it of any foreign substance which might have a tendency to be deposited thereon; a thumb-screw 34 is threaded into the lower end of valve stem 28 and is designed to operate in conjunction with a spring 25 35 to give positiveness to the valve return; this spring 35 bears against a shoulder 36.

The drawings show piston 23 to be made of a separate piece from the body of drive-arm 21, but threadedly attached thereto, 20 and to insure rigidity and security, I provide a split end 37 to the drive arm stud having a conical seat, and an expander 38 threaded in said stud; said expander having kerfs 39 in either end thereof adapted to 25 propel it. When the parts are being assembled the upper kerf 39 is used to expand split ends 37 until they are drive-fit to piston 23, the lower kerf being used to expand the split ends 37 to a perfect fit after it is 30 fully assembled. The drive arm and piston may be made of one piece instead of the structure as above described, without departing from the spirit of the invention.

I provide a valve 40 with a plurality of 45 flutings 41 on its periphery, and a stem 42 seated in a valve cage 44 on a valve seat 47. Said valve cage 44 has transverse perforations or ports 45 communicating with an annular groove 46 and which said ports 45 and 50 groove 46 register with an outlet manifold 50 in the cylinder head. The valve 40 is made positive in its action by a spring 43 encircling stem 42 and held positioned and alined in a nut cap 48. I preferably thread 55 valve cage 44 to a seating at top of the cylinder 6 but I may hold it to a seating by other means. The valve 40 and valve cage 44 are sealed by an enclosing cap 49 threaded into the cylinder head. By this design I 60 have immediate access to the only movable valves in the mechanism, which are vital factors in such a device. Removing cap 49 access is had immediately to valve 40 and removing cap 49 and cage 44 I have immediate access to valve 28 in the piston.

I provide longitudinal bores 51 in piston 23' having openings adjacent to wrist-pins 22 and the eccentric straps 20 whereby oil is pumped under pressure to the working parts in chamber 9, and also whereby a spray is constantly maintained in said chamber 9, the chamber 9 being used as an oil reservoir. Threaded into boss 2, I provide a bushing 52 extending into chamber 9, and I provide a washer 53 internal of said 75 chamber 9 between the inner face of said bushing 52 and a face of collar 13 on shaft 12; this washer 53 is preferably a material such as fibre. The bushing 2 with collar 13 and washer 53 in combination with spring 80 17 and the back pressure of the refrigerating medium in chamber 9 are designed to seal chamber 9 against leakage of oil or gas along the line of shaft 12. 54 is a washer intended to insure sealing the threading on bushing 52. 55 is a roller or other type of bearing assembled in bushing 52.

As shown, the device consists of three unitary elements interrelated and interdependent; viz., a housing enclosing the working mechanism; a driving element and a driven element; the driving element consisting of the shaft with the eccentrics locked thereon and a sealing collar is a single complete unit. The driven element consists of the drive arm and piston associated with the eccentric strap; the inlet valve is unitary with the driven element and the outlet valve is unitary with the housing element. The medium to be compressed 100 enters the housing, at 8, and passes to the spaced area 7 surrounding the cylinder, from thence it passes through ports 8' during the downward stroke of the piston into the piston through ports 25 and from thence through the piston into the compression chamber 6. When the piston begins its upward stroke the piston valve closes and the fluid when compressed passes the valve in the cylinder head and out through port 105 50. In practice, the refrigerating fluid is delivered to the machine as a gas at a certain temperature, and at a certain pressure, and is delivered out of the machine at a higher temperature and a higher pressure. 110 The efficiency of such a mechanism is in direct relation to the critical point of conversion of such fluid. This device automatically increases its efficiency as it operates, and automatically balances itself; the refrigerating medium being of a low temperature comes into contact with the compression chamber of the cylinder absorbing temperature therefrom, passing through the piston the piston is cooled thereby and when the fluid is compressed its temperature approximates a point of perfect 115 economical conversion.

The stroke of the piston is arranged so 120 that the piston rings never come into con- 125

- tact with any of the cylinder inlet ports and there is no open connection between any of the refrigerating fluid channels and chamber 9, but a pressure is built up in the 5 chamber 9 by reason of seepage of the refrigerating medium along the lines of the piston, and this seepage continues until the pressure in chamber 9 is equal to the pressure of the refrigerating medium as it is 10 delivered to the compressor on its suction or low side. To effect a simple and perfect sealing I take advantage of this condition; the collar 13 on the shaft 12 has its exposed face where the pressure in the 15 chamber 9 is exerted directly upon it and the line of the shaft 12, forcing and maintaining said shaft 12 with the collar 13 up against the washer 53 and the washer 53 is maintained by said pressure against the 20 face of the bushing 52; I also take advantage of the said pressure in chamber 9 operating on the inner end of the shaft 12 in boss 3; the spring 17 is designed to give initial longitudinal compression upon the 25 shaft 12 and then acts in combination with the gas pressure built up in the chamber 9 to sustain the sealing as described. The bearings are all large in proportion to the 30 mechanism. The connections between the driving element and the driven element is below the line of the driving element and always in direct alignment therewith and the strain of compression is taken when the 35 parts are in best position to sustain such strain. The strain of compression is always sustained in a direct line with the pistons activity, side thrust is reduced to a minimum and torsional strain is practically eliminated.
- 40 The device, as shown, has two cylinders, but the principles and construction are the same whether used with a single cylinder or a plurality of cylinders.
- What I claim is:
1. In a fluid compressor a cylinder having spaced walls defining a compression chamber and a cooling chamber surrounding said compression chamber, a chambered piston reciprocating in said compression chamber and means for reciprocating said piston, said cylinder and piston being provided with coacting ports establishing registering communication between the interior of said piston and the chamber surrounding said compression chamber for all positions of said piston.
  2. In a fluid compressor a cylinder having spaced walls defining a compression chamber and a cooling chamber surrounding said compression chamber, a chambered piston valve controlled reciprocating in said compression chamber and means for reciprocating said piston, said cylinder and piston being provided with coacting ports establishing communication between the interior of
- said piston and the chamber surrounding said compression chamber, a port in said piston and a port in said cylinder being always in registering communication for all 70 positions of said piston.
3. In a fluid compressor a casing constituting a fluid and liquid tight receptacle consisting of a cylinder having an integral cylinder head and provided with integral spaced inner and outer walls defining a compression chamber and a chamber encircling said compression chamber, integral therewith a shaft chamber and lubricant reservoir, and enclosing sealing plate below the level of the lubricant line.
4. In a fluid compressor a cylinder having an integral cylinder head and provided with integral spaced inner and outer walls defining a compression chamber and a chamber encircling said compression chamber, a 75 shaft casing integral with said cylinder, said shaft casing forming a lubricant reservoir, and enclosing sealing plate below the level of the lubricant whereby the back pressure of a fluid being compressed coats with and 80 upon said lubricant to seal the housing against gas emission.
5. In a fluid compressor a cylinder having spaced walls defining a compression chamber and a cooling chamber surrounding said 85 compression chamber, a chambered piston containing an automatically controlled valve reciprocating in said compression chamber and means for reciprocating said piston, said cylinder and piston being provided with coacting ports establishing registering communication between the interior of said piston and the chamber surrounding said compression chamber, the port in said piston being always in registry with a port in said cylinder.
6. In a fluid compressor a cylinder having spaced walls defining a compression chamber and a cooling chamber surrounding said 90 compression chamber, a chambered piston reciprocating in said compression chamber and means for reciprocating said piston, said cylinder and piston being provided with coacting ports establishing registering communication between the interior of said piston and the chamber surrounding said compression chamber, and said surrounding chamber extending endwise beyond said compression chamber.
7. In a machine for compressing a refrigerant, a cylinder having a compression chamber, a cooling chamber and a chambered piston, an inlet for refrigerant at comparatively low temperature and pressure into said cooling chamber and registering means for maintaining constant communication between the interior of said piston and said cooling chamber, said cooling chamber extending into the head of said cylinder beyond the end of said compression chamber.

8. In a machine for compressing a refrigerant, a cylinder having a compression chamber, a cooling chamber and a chambered piston, an inlet for refrigerant at comparatively low temperature and pressure into said cooling chamber and registering means for maintaining constant communication between the interior of said piston and said cooling chamber, said cooling chamber extending into the head of said cylinder beyond the end of said compression chamber, said inlet being near said cylinder head.
9. In a device of the character described, a cylinder, a shaft housing having a shaft opening, a shaft extending into said housing through said opening, and means for sealing the housing around said shaft against escape of fluid under pressure in said housing comprising a member on said shaft movable toward said housing by fluid pressure, said member having a flat face exposed to the pressure of said fluid.
10. In a device of the character described, a cylinder, a shaft housing having a shaft opening, a shaft extending into said housing through said opening, and means for sealing the housing around said shaft against escape of fluid under pressure in said housing comprising a member on said shaft movable toward said housing by fluid pressure, said member having a flat face exposed to the pressure of said fluid transverse to the direction of movement thereof, and a gasket mounted between the wall of said housing and said member.
11. In a fluid compressor, a cylinder having spaced walls defining a compression chamber and a cooling chamber surrounding said compression chamber, a chambered piston reciprocating in said compression chamber, automatic valve mechanism carried by said piston for establishing communication between said compression chamber and the interior of said piston when moving in one direction and sealing said chamber from said piston when moving in the opposite direction, and means for reciprocating said piston, said cylinder and piston being provided with co-acting ports establishing registering communication between the interior of said piston and the chamber surrounding said compression chamber for all positions of said piston.
12. In a fluid compressor, a casing constituting a fluid tight receptacle consisting of a cylinder having an integral cylinder head and provided with integral spaced inner and outer walls defining a compression chamber and a chamber encircling said compression chamber and integral therewith a shaft chamber and lubricant reservoir; and enclosing sealing plate below the level of the lubricant line; an actuating shaft extending into said casing, an eccentric in said casing operatively assembled on said shaft, a piston operating in said cylinder and an eccentric strap carried by said piston surrounding said eccentric.
13. In a fluid compressor, a casing constituting a fluid tight receptacle, an actuating shaft extending into said casing, an eccentric in said casing operatively assembled on said shaft, a cylinder, a piston operating therein and an eccentric strap carried by said piston surrounding said eccentric, said eccentric having a limited play relative to said strap axially of said shaft.
14. In a fluid compressor, a casing constituting a fluid tight receptacle, an actuating shaft extending into said casing, an eccentric in said casing operatively assembled on said shaft, a cylinder, a piston operating therein, an eccentric strap carried by said piston surrounding said eccentric, said eccentric having a limited play relative to said strap axially of said shaft, and means on said shaft for sealing the casing adjacent said shaft by axial pressure of said shaft.
15. In a fluid compressor, a casing constituting a fluid tight receptacle, an actuating shaft extending into said casing, an eccentric in said casing operatively positioned on said shaft, cylinders, pistons operating in said cylinders, and eccentric straps each co-operating with an eccentric surface of said eccentric member, the shaft assemblage having a limited axial play, each eccentric strap having means pivotally associating it with the piston member whereby the shaft may be automatically sustained in sealing relation to the housing.
16. A device for the purposes described, consisting of a cylinder and a shaft housing, a fluid compressing mechanism operating therein, a driving shaft projecting into and operating in said housing, a bushing encircling a portion of said shaft, a disk fixedly assembled on said shaft inside said housing and adjacent said bushing, a washer assembled on said shaft between a face of the disk and the inner face of the bushing in combination with a back pressure of the refrigerating medium acting upon the exposed surface of the disk whereby the fluid contents are sealed against emission.
17. In a mechanism of the class described, a straight drive shaft receiving power from an outside source, associated with an integral eccentric operably connected with drive arms said connection being in the case of each drivearm an eccentric strap pivotally associated with the drivearm and rotatively associated with the eccentric upon the shaft whereby pistons are driven in multiple, the said shaft having an axial play in relation to the eccentric straps and the pistons.
18. In a device of the character described, a cylinder, a shaft housing having a shaft opening, a shaft extending into said housing

through said opening, and means for sealing the housing around said shaft against escape of fluid under pressure in said housing comprising a member on said shaft movable toward said housing by fluid pressure, said member having a flat face exposed to the pressure of said fluid transverse to the direction of movement thereof, and a gasket of non-ferrous material mounted between the wall of said housing and said member.

19. In a device for the purposes described, a cylinder, a piston functioning therein, a chamber tributary to said cylinder, a piston functioning mechanism therein consisting of a driving shaft and driving connections; said drive shaft having connection with an external source of power, means for sealing said chamber and said shaft against fluid emission consisting of a disk unitary with said shaft, a washer assembled between said disk and a face of the shaft bearing, in combination with a tension element whereby said shaft is maintained fluid tight, and the back pressure of the refrigerating medium acting in the chamber against the exposed surface of the disk.

20. In a mechanism of the class described wherein a medium is compressed which said medium is delivered to the cylinder initially

at a pressure greater than atmospheric pressure; said mechanism comprising a cylinder, a piston functioning therein, a shaft housing, and a piston functioning mechanism in said housing, having association with a drive shaft receiving power from an external source, said shaft having thereon an annular flange, one face of said flange adapted to press and operate against a disk, which disk is in contact association with an inner face of a bearing bushing; the inner exposed face of the flange on the shaft coacting with a pressure exerted by the said medium to secure and maintain a sealing of said housing and shaft against the emission of the said medium along the line of said shaft.

21. In a gas compressor, in combination, a shaft chamber and associated therewith a cylinder with an exterior gas chamber, ports communicating the gas chamber with the cylinder, a piston having a valve controlled gas passage, ports in said piston constantly registering with the ports in the cylinder, a straight driveshaft having means whereby to automatically seal the shaft chamber. 55

Signed at Chicago, county of Cook, and State of Illinois, this 15th day of December, 1921.

WINFIELD SCOTT WILLIAMS.
